UNITED STATES PATENT OFFICE.

WILLIAM W. HUBBARD, OF MENDOTA, ILLINOIS.

WASHBOARD.

Application filed June 9, 1921. Serial No. 476,114.

To all whom it may concern:

Be it known that I, WILLIAM W. HUBBARD, a citizen of the United States, and a resident of Mendota, in the county of La Salle and State of Illinois, have invented certain new and useful Improvements in Washboards, of which the following is a specification, reference being had to the accompanying drawings, forming a part thereof.

This invention relates to improvements in wash boards and its object is to provide an improved rubbing surface for such boards adapted to facilitate the cleansing action and designed for economical manufacture. It consists of certain features and elements of the construction hereinafter described and shown in the drawings as indicated by the claims.

In the drawings:

Figure 1 is a partial front elevation of the wash board constructed in accordance with this invention.

Figure 2 shows a fragment of one of the grooved rollers in partially completed form.

Figure 3 illustrates a portion of one of the rollers in completed form.

Figure 4 is a view of the roller shown in Figure 3 taken from a position at 90 degrees from the point of view of said Figure 3.

Figure 5 is a vertical sectional view taken through several of these rollers.

As shown in Figure 1 the wash board embodying this invention comprises side frame members, 1, 1, between which there are mounted a series of parallel rollers, 2, which are corrugated to take the place of the more usual corrugated metal surface ordinarily provided. The rollers are preferably made of wood formed in a special manner as more clearly shown in Figures 3, 4 and 5. In the originally cylindrical stock of which the rollers, 2, are formed there are cut two oppositely helical grooves, 3, which, being of equal pitch intersect each other at opposite sides of the cylinder. As a result there remains a solid core, 2^a, from which there project two sets of ribs or corrugations, 4, each graduated in thickness and terminating in a point as at 5. The grooves between thickest portions of the ribs or corrugations, 4, represent the points at which the oppositely helical grooves, 3, coincide. If only a single groove of uniform pitch were cut from the stock the roller would present the appearance shown at 2^b, in Figure 2; it would merely have a running thread cut in its surface. However, the oppositely helical groove which forms the other thread cuts through the first thread resulting in the wedge shaped ribs, 4, each presenting a diamond shaped face, 6, at its widest portion and tapering therefrom in both directions to a terminal point, 5, on the surface of the core, 2^a. Alternating with the narrowing end portions, 7, of one set of ridges, 4, are the similar but oppositely pointed ends of the other set of ribs or ridges whose thickest portions project from the core, 2^a, at the part diametrically opposite the thick portions of the first set of ridges.

Each of the rollers, 2, is provided with trunnions or axles, 8, engaging the frame members, 1, so as to permit rotation of the rollers as the goods to be cleansed are rubbed over the corrugated surface which they provide. As indicated in Figure 5 the tapering form of the ribs, 4, gives to each roller an external outline which is elliptical in cross section instead of circular. The rollers are not connected or geared together; therefore as they are rotated each on its own axis by the movement of the goods over them the distance between adjacent rollers varies with the result that portions of the goods momentarily pressed between the rollers tend to be squeezed and then released. This, of course, aids the cleansing action by forcing the soap suds and water through the fabric. Furthermore on account of the tapered form of the corrugations or ridges, 4, any slipping of the goods upon the surface of the rollers results in a limited squeezing effect upon the portions engaged between adjacent ridges, 4; obviously any movement of the goods obliquely across the rollers will result in some friction between the goods and the corrugations of the rollers which will assist the cleansing action of the soap suds and water.

With this construction therefore the travel of the goods in any direction over the corrugated surface formed by the rollers, 2, is effective in assisting the cleansing action. And in practice it is found that not only is it unnecessary to rub the goods as briskly or as forcibly upon a wash board of this construction but that the work usually takes much less time than with a board of the common type.

The manufacture of the rollers is a comparatively simple matter and is accom-

plished by feeding the stock through two thread cutting dies operating simultaneously but turning in the opposite directions while the stock is held against rotation.

5 I claim:

1. A wash board comprising a frame and a plurality of rollers journaled therein, each having a corrugated surface composed of ribs tapering circumferentially in height, 10 and thus having elliptical profiles.

2. A wash board comprising a frame and a plurality of rollers journaled therein, each having a corrugated surface composed of ribs each extending over one-half way round 15 the roller standing in planes perpendicular to the roller axis and tapering circumferentially from their centers to their ends.

3. A washboard comprising a frame and rollers journalled therein formed with circumferentially extending ribs which taper in both directions circumferentially from maximum to minimum cross section, said ribs being spaced apart by cylindrical surfaces of the roller which taper circumferentially so that their minimum width occurs 25 between points of maximum cross section of the ribs.

4. A wash board comprising a frame and

a plurality of rollers journaled therein, each having a corrugated surface composed of 30 two sets of spaced ribs standing in planes transverse to the roller axis and tapering in both directions circumferentially from maximum to minimum thickness.

5. In the combination defined in claim 4, 35 the planes of one set of ribs alternating with the planes of the other set and the minimum portions of the ribs of one set interlapping with the minimum portions of the other ribs at opposite sides of the roller axis. 40

6. A wash board comprising a frame and a plurality of rollers journaled therein, each having a corrugated surface composed of two sets of spaced ribs standing respectively 45 in alternating planes transverse to the roller axis, said ribs tapering in both directions circumferentially from maximum to minimum height and the minimum portions of one set of ribs extending adjacent to the minimum portions of the others whereby 50 the external shape of the rollers is rendered elliptical.

In testimony whereof I have hereunto set my hand at Mendota, Illinois, this 6th day of June, 1921.

WILLIAM W. HUBBARD.
